UNITED STATES PATENT OFFICE.

WILLIAM H. JOHNSON, OF REVERE, MASSACHUSETTS.

DESIGN FOR A BUTTON-PIECE FOR SUSPENDERS.

SPECIFICATION forming part of Design No. 36,797, dated February 16, 1904.

Application filed January 22, 1904. Serial No. 190,241. Term of patent 3½ years.

To all whom it may concern:

Be it known that I, WILLIAM H. JOHNSON, a citizen of the United States, residing at Revere, in the county of Suffolk and State of Massachusetts, have invented a new, original, and ornamental Design for a Button-Piece for Suspenders, of which the following is a specification, reference being had to the accompanying drawing, forming a part hereof.

10 The figure of the drawing is a plan view of a button-piece for suspenders, showing my new and ornamental design.

What I claim as new, and desire to secure by Letters Patent, is—

The ornamental design for a button-piece for suspenders, as herein shown.

In testimony whereof I have hereunto set my hand, in presence of two subscribing witnesses, this 6th day of January, 1904.

WILLIAM H. JOHNSON.
